(57) **CLAIM**

The ornamental design for a user interface for a display screen, as shown and described.

DESCRIPTION

FIG. 1 is a front view of a user interface for a display screen, showing the new design.

The broken line drawing of a portion of a display screen is for illustrative purposes only and forms no part of the claimed design. Unseen portions of the display screen form no part of the claimed design.

1 Claim, 1 Drawing Sheet
